[57] CLAIM

The ornamental design for a rotary motion transducer
with multiple mounting orientations, as shown and de-
scribed.

DESCRIPTION

FIG. 1 is a top front right side elevational view of a
rotary motion transducer with multiple mounting ori-
entations showing our new design;

FIG. 2 is a front elevational view thereof;

FIG. 3 is a back elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a partial back elevational view, with portions
of the housing being shown in phantom lines which are
identical to that shown in FIG. 3. The cap is removed
for ease of illustration; and,

FIG. 9 is a back elevational view of the cap thereof.
